UNITED STATES PATENT OFFICE.

CHARLES MALOUF AND NICHOLAS MALOUF, OF CHICAGO, ILLINOIS.

COIN-CONTROLLED CLOCK.

Application filed November 25, 1921. Serial No. 517,575.

To all whom it may concern:

Be it known that we, CHARLES MALOUF and NICHOLAS MALOUF, both citizens of the United States, and residents of the city of Chicago, in the county of Cook and State of Illinois, have invented a new and useful Improvement in Coin-Controlled Clocks, of which the following is a full, clear, and exact description.

10 Our invention relates to improvements in coin controlled clocks, and it consists in the combinations, constructions, and arrangements herein described and claimed.

An object of our invention is to provide 15 an improvement over that form of the device shown in our co-pending application, filed November 25, 1921, Serial No. 517,576. In said application there is disclosed a coin controlled clock in which the winding stem 20 is prevented from rotation in either direction unless a coin is inserted in the box. It is obvious therefore that only a certain type of clock can be used with this device, i. e., a clock in which the winding stem does 25 not rotate in a direction opposite to the winding direction when the clock is running. The construction of the present device is primarily designed to obviate the necessity of having to use only a certain 30 type of clock, that is, this device can be used with a clock in which the stem rotates as the clock unwinds.

A further object of our invention is to 35 provide a device of the type described in which the winding stem is still held in locked position when only pennies are inserted in the device, thus compelling the person owning the clock to periodically insert coins of a larger denomination than 40 that of a penny in order to keep the clock running.

A further object of our invention is to 45 provide a device of the character described which consists of a minimum number of parts, is inexpensive to manufacture, and which is not likely to easily get out of order.

Other objects and advantages will appear 50 in the following specification, and the novel features of the invention will be particularly pointed out in the appended claims.

Our invention is illustrated in the accompanying drawings, forming part of this application, in which—

Figure 1 is a section along the line 1—1 55 of Figure 2, and

Figure 2 is a section along the line 2—2 of Figure 1.

In carrying out our invention, we provide a casing 1 in which is mounted a clock mechanism indicated generally at 2. The 60 clock mechanism 2 is provided with the ordinary winding stem 3, which projects through the rear wall 4 of the casing 1. The winding stem 3 is adapted to be rotated in the direction of the arrow in Figure 1 when 65 the clock is wound and to rotate in the direction opposite to the direction of the arrow when the clock spring is unwinding. The clock forms no part of our invention except in so far as it cooperates with the 70 parts about to be described.

A star wheel 5 is rigidly mounted to the stem 3 and is adapted to rotate therewith. The casing 1 is provided with an inclined coin chute 6 which is curved at the lower 75 end thereof. A wall 7 of the chute 6 is cut away for a portion of the length thereof and a coin is prevented from moving through this cut away portion by means of an arm 9 and a dog 10. As will be seen in Figures 1 and 2, the arm 9 is rigidly mounted on a stub shaft 11 which is in turn rotatably mounted in the rear wall 4. A spring 12 is secured to the free end of the arm 9 and to the casing 1. In like manner, the dog 10 is mounted on a stub shaft 13 which is carried by the rear wall 4. The spring 14 normally keeps the dog 10 in engagement with a lug 15, the latter being carried by the 80 wall 4. The dog 10 has one of its sides provided with two curved portions 16 and 17 for a purpose hereafter described. The arm 9 can be manually swung downwardly into the chute 6 by means of a handle 18.

A means for normally preventing the rotation of the star wheel 5 in the direction of the arrow and for permitting a rotation thereof in the opposite direction is provided and comprises a sector 19 which is pivotally mounted on a rod 20, the latter being carried by the wall 4. The sector 19 carries a pawl 21 which is adapted to engage the teeth of the star wheel 5 so as to normally prevent the rotation of the wheel in the direction of the arrow. The pawl 21 has a lug 23 projecting laterally therefrom which is adapted to rest on one edge of the sector 19. The sector 19 also carries a leaf spring 22 which engages the lug 23. A spring 24 has one of its ends secured to a pin 25 and 105 110

its other end to the sector 19 and is adapted to keep the pawl 21 in engagement with the star wheel 5. One edge of the sector 19 has a hook-like projection 26 integral therewith 5 and which is adapted to be engaged by a pawl 27. As will be seen in Figure 1, the pawl 27 is pivotally mounted on a pin 28. A leaf spring 29 yieldingly keeps the pawl 27 in engagement with the sector 19. A 10 toothed wheel 30 is rotatably carried by the pawl 27 and is disposed adjacent the free end thereof.

From the foregoing description of the various parts of the device, the operation 15 thereof may be readily understood. In case the clock has to be wound, a coin, such as a nickel, is first inserted in the chute 6. The coin will drop to the position shown in Figure 1 and will rest against the dog 10 20 and the side 31 of the chute. The handle 18 is then rotated in an anti-clockwise direction, thus causing the arm 9 to swing downwardly into the chute 6 and to force the coin out of the chute 6 and into the casing 1. 25 This operation swings the dog 10 about the rod 13. The coin in passing out of the chute 6 strikes the sector 19 and swings it in a clockwise direction against the tension of the spring 24. The sector 19 carries with it 30 the pawl 21 and it will therefore be seen that the star wheel 5 is freed and is permitted to rotate in the direction of the arrow, thereby permitting the stem 3 to be rotated so as to wind the clock. The pawl 21 is 35 held out of engagement with the wheel 5, since the pawl 27 engages with the projection 26 and prevents the sector 19 from resuming its normal position. As the clock 2 starts unwinding, the stem 3 and the wheel 40 5 will be rotated in a clockwise direction. One of the teeth on the wheel 5 will therefore abut against one of the teeth of the wheel 30 and will swing the wheel 30 with the pawl 27 against the tension of the spring 45 29, thereby releasing the sector 19 and permitting the spring 24 to return it to its normal position. When the sector 19 assumes its normal position, the pawl 21 engages with the teeth on the wheel 5 and prevents the 50 rotation of the wheel 5 in the direction of the arrow until another coin has been inserted into the chute 6. It is obvious, however, that the wheel 5 is permitted to rotate with the stem 3 as the clock unwinds, since 55 the pawl 21 will be moved outwardly against the tension of the spring 22 as the teeth of the wheel 5 move beneath the pawl. When the pawl 27 is swung into engagement with the sector 19 so as to free the pawl 21 from 60 the wheel 5, the rotation of the wheel 5, which is caused by winding the clock, will merely rotate the wheel 30. On the other hand, the wheel 30 is so constructed that

when the wheel 5 rotates in a clockwise direction, it will not rotate the wheel 30 but 65 will move the latter with the pawl 27 against the tension of the spring 29 as heretofore described.

Assume that a penny is dropped into the chute 6 instead of a nickel or a coin of a larger denomination. The penny being larger in diameter than a dime will fall into the curved portion 17 of the dog 10. The arm 9 can now be swung by means of the handle 18 and will eject the penny from the 75 chute 6. Since the penny is received in the curved portion 17 of the dog 10, the penny will not strike the sector 19 so as to rotate the latter, since the diameter of the penny is not large enough to abut the curved 80 portion 17 and the sector 19. Coins of larger diameters, such as nickels, quarters, etc., will be received in the curved portion 17 of the dog 10 and will swing the sector 19 when they are ejected from the chute 6 by means of the arm 9. The curved portion 16 of the dog 10 is adapted to receive a dime and as will be seen in Figure 1, is disposed nearer the sector 19 than is the 85 curved portion 17. Therefore, when the dime is ejected from the chute 6 by means of the arm 9, the diameter of the dime is large enough to abut the curved portion and the sector 19 at the same time. It will therefore be apparent that we have provided a 90 device in which a coin of a larger denomination than a penny has to be periodically deposited therein before the clock can be wound. It will also be apparent that the device automatically resets itself after the 95 clock has been running for a short length of time.

We claim:

The combination with a clock having a winding stem, said stem rotating in a reverse direction to said winding direction when said clock is unwinding, of a toothed wheel carried by said stem, a casing, a sector pivotally carried by said casing, a pawl carried by said sector and normally engaging said wheel for preventing said stem from rotating to wind said clock, a coin chute carried by said casing, a movable stop member for stopping a coin, a manually operated arm adapted to move said coin into engagement with said sector, whereby said sector is swung and releases said pawl from said wheel, a second pawl adapted to lock said sector after said sector has been swung by the coin, and a second toothed wheel carried by said second named pawl and being adapted to disengage said second named pawl from said sector when said stem is rotating in the reverse direction.

CHARLES MALOUF.
NICHOLAS MALOUF.
